(57) **CLAIM**

The ornamental design of a turf fiber, as shown and described.

DESCRIPTION

FIG. 1 is a perspective view of a turf fiber embodying the design of the present invention;

FIG. 2 is a top view of the turf fiber illustrated in FIG. 1; FIG. 3 is a bottom view of the turf fiber illustrated in FIG. 1;

FIG. 4 is a front view of the turf fiber illustrated in FIG. 1;

FIG. 5 is a rear view of the turf fiber illustrated in FIG. 1;

FIG. 6 is a left side view of the turf fiber illustrated in FIG. 1; and,

FIG. 7 is a right side view of the turf fiber illustrated in FIG. 1.

1 Claim, 4 Drawing Sheets
